UNITED STATES PATENT OFFICE.

THOMAS W. BROWN, OF BOSTON, MASSACHUSETTS.

SKATE.

Specification of Letters Patent No. 22,932, dated February 15, 1859.

To all whom it may concern:

Be it known that I, THOMAS W. BROWN, of Boston, in the county of Suffolk and State of Massachusetts, have invented an Improved Skate; and I do hereby declare that the same is fully described and represented in the following specification and the accompanying drawings, of which—

Figure 1, is a top view. Figs. 2, and 3, 10 side elevations, and Figs. 4 and 5, transverse sections of it, the two sections being taken through the devices by which the toe and heel plates are connected to the runner.

15 My said skate combines the advantages of the rocker skate and the angular heel or straight runner skate, and can be used as either. What is meant by the "rocker," is a skate having the bearing edge of its 20 runner curved both at the toe and the heel and made straight or slightly curved between the same.

Fig. 6 will serve to illustrate the form of the "rocker runner." The angular heel 25 runner is exhibited in Fig. 7. In this runner the heel is made angular as shown at *a*, while the front or toe end of the runner is curved as shown at *b*. The bearing edge, *c*, is usually made straight.

30 In my improved skate as shown in Figs. 1, 2, 3, 4, and 5, *A*, denotes the runner, *B*, the toe plate or that on which the front part of the foot rests. *C*, is the heel plate and *D*, the heel screw.

35 In carrying out my invention, I form the runner *A*, with one edge, *a b c d*, having the shape or configuration of the bearing edge of the common rocker skate and I construct the opposite edge viz., *a c d*, like the bearing edge of the angular heel 40 skate making at *d* an angular heel.

The heel screw *C*, projects from a standard *E*, which bears by a shoulder on the top edge and extends down on one side of 45 the runner and is secured to it by a screw *f*, which goes through the standard and is screwed into the runner. The toe or ball plate *B*, is fastened to the runner by similar devices, as shown at *F*, and *g*. Furthermore, 50 the heel plate screws upon the screw *D*, so as to be adjustable with reference to the upper end of the screw, or in other words, at a greater or less distance there-

from, as circumstances may require. The object of this is to enable a person to extend the screw into the heel of his shoe or boot as far as he may desire and afterward turn the heel rest up against the heel so as to insure a firm bearing of the heel on the skate and prevent the screw from working out of the heel. The holes in the runners that are to receive the screws, *f*, *g*, should be made in or very near the middle of it in order to enable the runner to be reversed, that is so as to have its upper edge turned downward whenever occasion 60 may require.

With the angular heel skate or "straight iron skate" as it is frequently termed, a person in order to stop himself while skating has only to elevate the toes of his feet so as to bring the sharp angles of the heels of the runners into close bearing upon the ice. They will cut into it and soon more or less or entirely check his motion. He 70 cannot, however, operate in this manner with the "rocker skate," but must adopt a different process as is well known to those who use such. For swiftness of motion the rocker is generally preferred to the angular heel runner. In my improved runner, each edge is curved at the toe while but one is curved at the heel. This enables the runner to be used with either edge 80 downward so that the advantages of both 85 kinds of skate are possessed by it.

I usually construct the front or ball rest *B*, of thin sheet metal, and furnish it with short spurs or studs, *i*, *i*, to enter the sole of a person's shoe when the skate is applied thereto. In order to fasten the skate on the foot, leather straps may be used and they may be carried under the heel and toe plates and about the foot as circumstances may require. For facilitating the fixation of the skate to the foot of a person as well as to render it lighter than it would otherwise be, the runner may be formed with openings *k*, *l*, *m*, through which the straps may be carried if desirable.

I claim—

1. The rocker and angular heel or straight edge runner made substantially in manner as described and applied to the bearing 105 plates or their equivalent so as to be capa-

ble of being reversed with respect to the same and used with either edge downward as may be desirable.

2. I also claim the application of the heel plate to the heel screw so as to be adjustable on or with reference thereto substantially in manner and for the purpose as described.

In testimony whereof, I have hereunto set my signature.

THOMAS W. BROWN.
